UNITED STATES PATENT OFFICE.

WILLIAM C. LANTZ, OF SOUTH BEND, INDIANA.

DESIGN FOR A SUPPOSITORY.

SPECIFICATION forming part of Design No. 31,133, dated July 4, 1899.

Application filed November 2, 1898. Serial No. 695,333. Term of patent 14 years.

To all whom it may concern:

Be it known that I, WILLIAM C. LANTZ, a citizen of the United States, residing at South Bend, in the county of St. Joseph, in the State of Indiana, have invented and produced a new and original Design for Suppositories, of which the following is a specification, reference being made to the accompanying drawings, forming part thereof.

Figure 1 is a transverse cross-sectional view of my suppository. Fig. 2 is a horizontal sectional view of the same. Fig. 3 is a side view of the same. Fig. 4 is a perspective view of the suppository.

In the drawings is shown a suppository having the similarly-convexed top A and bottom B, whose ends and edges merge into the surrounding central band C, whose sides are parallel, as shown in cross-section, and whose ends D are nearly semicircular in shape.

What I claim is—

The design for a suppository substantially as herein shown and described.

WILLIAM C. LANTZ.
